(57) **CLAIM**

The ornamental design for a motion detection device as shown and described.

DESCRIPTION

FIG. 1 is a top view of a motion detection device shown in a state of use mounted on a chair.

FIG. 2 is an enlarged perspective view of a motion detection device shown in a state of use mounted on a chair.

FIG. 3 is a front view of a motion detection device shown in a state of use mounted on a chair.

FIG. 4 is a back view of a motion detection device shown in a state of use mounted on a chair.

FIG. 5 is a left view of a motion detection device shown in a state of use mounted on a chair.

FIG. 6 is a right view of a motion detection device shown in a state of use mounted on a chair.

FIG. 7 is a top view of a motion detection device shown in a state of use mounted on a chair.

FIG. 8 is a bottom view of a motion detection device shown in a state of use mounted on a chair.

FIG. 9 is a top perspective view of a motion detection device.

FIG. 10 is a bottom perspective view of a motion detection device.

FIG. 11 is a rear view of a motion detection device.

FIG. 12 is a front view of a motion detection device.

FIG. 13 is a left view of a motion detection device.

FIG. 14 is a right view of a motion detection device.

FIG. 15 is a top view of a motion detection device; and,

FIG. 16 is a bottom view of a motion detection device.

In the drawings, the dot-dash broken lines depict the boundaries of the enlarged views in FIGS. 2 and 10 and form no part of the claimed design.

In the drawings, the broken lines depict portions of the motion detection device that form no part of the claimed design.
